UNITED STATES PATENT OFFICE.

WILLARD A. WOODWARD, OF FAIRBANKS, WASHINGTON.

POWER-GOVERNOR AND CLUTCH.

1,203,833.

Specification of Letters Patent.

Patented Nov. 7, 1916.

Application filed June 8, 1914. Serial No. 843,688.

To all whom it may concern:

Be it known that I, WILLARD A. WOODWARD, a citizen of the United States, residing at Fairbanks, in the county of Whitman and State of Washington, have invented a new and useful Power-Governor and Clutch, of which the following is a specification:

My invention relates to improvements in power drive wheels in which the power from the band wheel is automatically applied to or released from the load by the speed of the wheel, and the objects of my invention are to provide a simple and positive means for applying or releasing the power applied to power driven machinery, such as the feed mechanism of a threshing machine, both automatically and manually. I attain these objects by the mechanism illustrated in the accompanying drawing, in which—

Figure 1 is a view showing the construction of the inner side of the band wheel; Fig. 2 is a diametrical cross-section of my device complete; Fig. 3 is a view of the construction of the outer side of the band wheel; Fig. 4 is a side view of my device complete; Fig. 5 is a detail view of the lever operating the clutch.

Similar characters refer to similar parts throughout the several views.

Referring to the drawing, 1 is a power or drive shaft on which is mounted a disk 2 having a cylindrical sleeve 3 inclosing the shaft 1, and a flange 4. On the cylindrical sleeve 3 is mounted a drive or band wheel 5 so that the spokes of the wheel revolve near to the disk 2. Attached to the spokes 6—6 of the wheel 5 on the side next to the disk 2 by pivots 7—7 are the segments 8—8 on which are mounted adjustable weights 9—9. Attached to the pivotal sleeves 10—10 of the segments 8—8 are lugs 11—11, to which are attached friction bands 12—12, the ends of the bands 12—12 having threaded projections 13—13 passing through holes in the lugs 11—11, and adjustably attached thereto by nuts 14—14. The other ends of the friction bands 12—12 are attached to the wheel 5 near the flange 4 of the disk 2, as at 15—15. It is apparent from this construction that the centrifugal force of the wheel 5 when in motion will be communicated to the segments 8—8, thereby throwing them outward from the center, thus causing the lugs 11—11 to draw the friction bands 12—12 down in contact with the flange 4 with sufficient

force to cause the wheel 5 and the disk 2 to revolve as a unit. The rate of speed at which this occurs can be regulated by adjusting the weights 9—9 on the segments 8—8 and increasing or diminishing the tension on the springs 8'—8' connecting the ends of the segments 8—8 with the wheel 5. To apply the power so communicated to the disk 2 by the band wheel 5, to the shaft 1, a gland 16 is solidly mounted on the shaft 1 by a sleeve 17. On the gland 16 are slidably mounted blocks 18—18, the outer faces of which are curved to conform to the inner face of the flange 4. Slidably mounted upon the sleeve 17 of the gland 16 is a sleeve 19, to which is attached a lever 20, the sleeve 19 and the blocks 18—18 being connected by bars 21—21, each pivoted at one end to the sleeve and at the other end to a block. The blocks 18—18 are connected by springs 22—22, which are only of sufficient strength to hold the blocks 18—18 away from the disk 4 when power is not desired.

It will be understood that when the blocks 18—18 are moved into contact with the flange 4, the power communicated to the flange 4 by the band wheel 5 will be communicated to the shaft 1 so long as the speed of the band wheel 5 is such as to exert the requisite centrifugal force on the segments 8—8 to bind the friction bands 12—12 onto the face of the flange 4. Thus the power applied to the shaft 1 is automatically controlled by the speed of the wheel 5, and also manually by the lever 20, giving a wide range of control, which is very useful in various forms of power driven machinery. For instance, the automatic device is designed to control the feed mechanism of a threshing machine when the speed of the engine varies. When the speed of the engine is sufficiently high to properly take care of the grain as fed, the automatic device serves to connect the power to the feed, but should the speed of the engine drop so that the material fed cannot be taken care of by the machine, then the feed mechanism is automatically cut off until such time as the speed rises to the proper point.

Up to this point, the automatic mechanism works independently of everything else, and accomplishes a result of its own. But if a break should occur in some other part of the mechanism of the threshing machine, necessitating the stopping of the feed con-

trol at once, before the speed falls to such a point that the automatic device will cut it out, the manually operated or controlled device is thrown off at once. Without a 5 manually operated cut off, the feed mechanism, under said circumstances, will usually continue to operate long enough before stopped by the automatic mechanism, to jam the cylinder and the rest of the 10 machine to such a point as to clog the entire machine.

The above is given as a preferred embodiment of my invention, although changes may be made in details of construction.

15 Having thus fully described my invention, what I claim and desire to secure by Letters Patent is—

1. The combination of a power shaft, a 20 disk and a drive wheel revolvably mounted on the shaft, automatic means to apply the power from the drive wheel to the disk, and manually controlled means to apply and release the power from the disk to and from the shaft.

25 2. The combination of a power shaft, a disk provided with a flange revolvably

mounted on the shaft by a cylindrical sleeve, a power wheel revolvably mounted upon the sleeve of the disk, centrifugal means to apply the power from the wheel to the disk, 30 and manual means to apply the power from the flange to the shaft.

3. The combination of a power shaft, a drive wheel and a disk provided with a flange revolvably mounted on the shaft, automatic means to apply the power from the wheel to the disk, and means to apply the power from the disk to the shaft, consisting of a gland solidly attached to the shaft, blocks slidably attached to the gland having 40 convex faces adapted to bear upon the inner face of the flange, a sleeve slidably mounted upon the shaft, bars pivoted at each end connecting the sleeve with the blocks, and manual means to slide the sleeve and move the 45 blocks into and out of contact with the flange.

WILLARD A. WOODWARD.
